UNITED STATES PATENT OFFICE.

DELAMAR C. BRIGGS, OF DETROIT, MICHIGAN, ASSIGNOR TO DETROIT STEEL PRODUCTS COMPANY, OF DETROIT, MICHIGAN, A CORPORATION OF MICHIGAN.

ADJUSTABLE HINGE FOR METALLIC-WINDOW VENTILATORS.

1,101,249.

Specification of Letters Patent. Patented June 23, 1914.

Application filed April 24, 1913. Serial No. 763,366.

To all whom it may concern:

Be it known that I, DELAMAR C. BRIGGS, a citizen of the United States of America, residing at Detroit, in the county of Wayne 5 and State of Michigan, have invented certain new and useful Improvements in Adjustable Hinges for Metallic-Window Ventilators, of which the following is a specification, reference being had therein to the 10 accompanying drawings.

The invention relates to metallic window constructions, and comprises the peculiar construction of an adjustable hinge connection between the stationary and swinging 15 sections of the window sash.

In the drawings: Figure 1 is a horizontal section through adjacent portions of a stationary and swinging sash member showing the hinge connection therebetween; Fig. 2 20 is a side elevation of the hinged members detached from each other; and Fig. 3 is a vertical section in the plane of the pivot.

A and B are the adjacent bars of the swinging and stationary sash sections, which, 25 as shown, are in the form of T-bars having molded heads and parallel spaced stems.

C and D are hinge members, each of which is provided with a shank portion E extending parallel to the stem of its respective 30 bar A or B and an outwardly-projecting ear portion F. One of the ears F has a round aperture G therein for receiving a pivot H, while the other ear is provided with a vertically slotted aperture I for receiving a 35 shank J of the pin H. The pivot H is preferably a shoulder screw, the shank J being threaded to receive a clamping nut K, the arrangement being such as to permit of vertically adjusting the pin in relation to the 40 ear F. The shanks E may be secured to the stems of the bars A and B by any suitable means, such as riveting.

In use, the members C and D may be secured to the bars A and B without necessity 45 of accurate positioning on said bars in relation to each other. When the swinging sash is hung, the clamping nut K is loosened, permitting of raising or lowering the shank J of the pin H until the proper adjustment 50 is obtained, after which the nut is tightened to hold the parts in this adjustment.

What I claim as my invention is:

1. In a metallic window, the combination with adjacent bars of stationary and swinging sash sections having parallel spaced portions, of a hinge comprising co-operating members each having a shank portion lying adjacent to one of said bars and an outwardly-projecting ear portion, a pin pivotally engaging one of said ears and having 55 a shouldered threaded shank engaging a vertical slot in the other of said ears, and a clamping nut engaging said shank and co-operating with said shoulder to clamp said pin in its adjusted position in said vertical 60 slot.

2. In a metallic window, the combination with adjacent bars of stationary and swinging sash sections having parallel spaced portions, of a hinge comprising co-operating 70 members, each having a shank portion lying adjacent to one of said bars and an outwardly-projecting ear portion, one of said ears having a round aperture therein and the other a vertically-extending slot, a shouldered pin having a head portion for engaging said round aperture and a shank portion of lesser diameter for engaging said slot, and a clamping nut for engaging the threaded end of said shank portion to clamp 75 said shoulder in different positions of adjustment.

3. In a metallic window, the combination with adjacent bars of stationary and swinging sash sections having parallel spaced portions, of a hinge comprising separable co-operating members fixedly secured respectively to said spaced parallel portions of the bars and projecting outward therefrom, one of said members being provided with a round 85 pivot aperture, and a pin engaging said aperture and adjustably clamped to the other 90 of said members.

In testimony whereof I affix my signature in presence of two witnesses.

DELAMAR C. BRIGGS.
